UNITED STATES PATENT OFFICE.

DENNIS McCOLGAN, OF BUTTE CITY, MONTANA TERRITORY.

ROTARY ENGINE.

SPECIFICATION forming part of Letters Patent No. 324,863, dated August 25, 1885.

Application filed October 29, 1884. (No model.)

To all whom it may concern:

Be it known that I, DENNIS McCOLGAN, of Butte City, in the county of Custer and Territory of Montana, have invented a new and Improved Rotary Engine, of which the following is a full, clear, and exact description.

My invention consists in certain new and useful improvements in the rotary engine for which United States Letters Patent No. 301,618, were issued to me July 8, 1884, which consists of a wheel having a U-shaped groove in its face forming the cylinder or steamway. The grooved wheel is surrounded by a circular casing or wheel, which fits closely against the grooved wheel and forms the outside of the steamway. The wheel carries the pistons, which are fixed on it, and abutments are arranged in the stationary ring to slide forward and backward to allow the pistons to pass. Slide-valves are also arranged in the stationary ring to shut off the steam while the abutments are being shifted, and the said valves and the abutments are operated by cams on the shaft of the wheel, whereby a simple and efficient rotary engine of large radius is obtained for developing great power with slow motion.

The present improvements consist in contrivances of the valve-gear, ports, and reversing-valves for reversing the engine, and also in various parts and details and combinations of the same, as will be fully described and set forth hereinafter.

Reference is to be had to the accompanying drawings, forming part of this specification, in which similar letters of reference indicate corresponding parts in all the figures.

Figure 1 is a sectional plan view of my improved engine, parts being broken away. Fig. 2 is a side elevation of the same, parts being broken away and others shown in section on line $x-x$, Fig. 1. Fig. 3 is a longitudinal sectional elevation of the engine. Fig. 4 is a cross-sectional elevation of the same, a part being broken out. Fig. 5 is a cross-sectional view of the rim part of the wheel, showing one of the pistons in section. Fig. 6 is a sectional view of Fig. 5 on the line $y-y$. Fig. 7 is a face view of the cams for forcing back the abutments. Fig. 8 is a face view of the

cam for operating the slide-valves. Fig. 9 is a detail sectional plan view of part of the machine, showing the arrangement of the valves. Fig. 10 is a detail cross-sectional view on the line $w-w$, Fig. 9. Fig. 11 is a longitudinal sectional view on the line $v-v$, Fig. 9. Fig. 12 is a sectional view on the line $z-z$, Fig. 9.

The wheel A, having a U-shaped groove, B, in its rim A', is mounted on a shaft, C, supported in bearings C', and the said wheel runs within a stationary circular case or fixed wheel, D, fitting closely against the wheel A, and provided with two annular grooves, D', one on each side, in which grooves packing-strips D'' are held, which are pressed against the rim of the wheel by adjusting-screws D'', where by a steam-tight joint is formed between the wheel A and its casing D. The groove B forms the steamway or steam-cylinder in which the steam acts, and in the said groove a series of pistons or transverse partitions, E, are arranged, of which three are shown in the annexed drawings, but more may be provided, if desired. Each piston is formed of two transverse walls, E', united by a cross-plate, E'', uniting the sides of the groove B a short distance from the outer edges of the sides of the groove. A packing-plate, F, rests on the outer surface of the plate E'', and is provided with two inwardly-projecting stems, F', having heads F'' on the inner ends, between which heads and the inner surface of the cross-piece E'' spiral springs F''' surround the stems F' and press the packing-plate F against the outer surface of the cross-piece E''. In the outer surface of the cross-piece E'' a transverse groove, e, is formed, extending from one partition E' to the other, and at each end of the groove e an aperture e' is formed in each partition. A valve, f, is held loosely in the groove e, and from the groove e an aperture e'' conducts the steam to the outer side of the cross-piece E'', so that the steam can act on the packing-plate F. When the steam acts on the piston in the direction of the arrow a', Figs. 3 and 6, it enters the corresponding aperture e', passes into the groove e, and presses the valve f against the opposite opening e', to prevent the steam from passing entirely through the piston. The steam then has no

other outlet than the aperture e^2 , and must act upon the packing-plate F, which it forces firmly against the inner circular surface of the casing D, thereby forming an absolutely-tight joint. As soon as the piston has passed the exhaust, and the steam that has been acting on the piston is exhausted, the springs F³ pull the packing-plate F inward toward the base of the groove B and from the inner face 10 of the casing D, thereby preventing friction. As soon as steam again acts on the said piston part of the steam enters the piston in the manner above described, and presses the packing-plate F against the inner face of the casing D. The steam can enter at either side of the piston, the opening in that side of the piston opposite the one at which steam enters being automatically closed by the valve f. Two exhaust-pipes, G, project from the casing 15 D diametrically opposite each other, one projecting upward and the other downward.

In horizontally-placed boxes or chests H, on the supporting-frame C², T-shaped abutments J are held to slide toward and from the rim of the wheel, the said boxes H, containing the abutments, being connected with and forming parts of the casing D. The boxes H are arranged diametrically opposite each other on the horizontal central axis of the machine. 20 On each side of the central shank of each abutment a packing-plate, J', is held, which is pressed against the sides of the box H and the sides of the groove B of the wheel A by suitable springs contained in recesses of 25 the said shank, thus forming tight and close joints.

On each end of the rear or outer cross-piece, J², of the abutment a rod, K, is secured, which projects through the box H, the said rods being at the sides of the wheel A and casing D, as shown in Fig. 9, the free ends of the rods being connected by suitable connecting-rods with levers operated by cams, as will be described hereinafter.

45 In the outer face of each abutment a cylindrical aperture, L, is formed, containing a piston, L', formed on the free end of a steam-conducting tube, L², projecting from the inner surface of the outer side of the box H toward the shaft C. The said tube L² is connected by a pipe, L³, with a steam-chest, M. In the steam-chest the slide-valve N is arranged, which may be replaced by a rocking or other valve, if desired. The said valve is attached 50 to the valve-rod N', projecting from the inner face of the box H, adjacent to the corresponding rod K. From the steam-chest M a channel, O, leads into a chamber, P, which is in communication with top and bottom steam-55 outlets Q, formed in the top and bottom of the box H above and below the abutment, and from which steam-outlets the steam passes into the steamway or groove B. In the said chamber P an elongated valve, P', works up and 60 down, and is secured to a rod, P², pivoted to an arm, P³, mounted on one end of a shaft, R, parallel with the side of the machine and suit-

ably journaled in standards in the boxes H. The valve P' has its bottom and top beveled or otherwise shaped in such a manner as to 70 adapt it to close the top and bottom of the chamber P.

Adjacent to the channel O, and between the steam-chest M and the chamber P, a chamber, S, is formed, in which a valve, S', works up 75 and down, the said valve being connected by a rod, s, with a lever, S², pivoted on a standard, S³, on the top of the box H.

A channel, S⁴, establishes communication between the steam-chest and the chamber S, 80 and a channel, S⁵, establishes communication between the channel O and the chamber S.

The rods s and P² work through suitable stuffing-boxes in the top of the box H.

On one side of the hub of the wheel A two 85 cam-disks, T and T', are mounted on the shaft C, which act on cam-levers U, connected by rods U' with the valve-rods N'. The cam T acts on the outer ends of the levers U, and thus draws the valves toward each other—that 90 is, toward the shaft—and the cam T', acting on those ends of the levers U to which the rods U' are pivoted, pushes the valves in the reverse direction. Each rod K, secured to one end of the cross piece J² of an abutment, is 95 connected by a connecting-rod, V, with the inner end of a lever, W, pivoted to swing in the horizontal plane upon a bracket, C, on the frame C², so that two levers, W, will be arranged at each side of the machine, and at 100 the opposite sides of the shaft.

On the outer end of each lever, W, a roller, W', is pivoted at the outer edge, and a like distance from the pivot on the inner end of the lever W a roller, W², is pivoted at the 105 inner edge of the lever.

On each end of the shaft C a sleeve, a, is mounted, which is provided at its outer end with a flanged disk, b, on the inner edge of which inwardly-projecting flange the cam-teeth c are formed, and on the inner end of each sleeve a the cam-ring d is formed. 110

Adjacent to the inner cam-ring, d, an annular groove, g, is provided in the sleeve, into which groove the prongs of a fork, h, pass, 115 which fork is formed on the lower end of a lever, j, pivoted on an arm, i, of the frame.

The cam rings or disks T' must be mounted on the shaft in such a manner that they can turn one-sixth of a revolution independently 120 of the shaft, and to permit of this I have provided each cam-ring, T', on its inner surface, with a circular groove, l, into which a stud or pin, k, projects from the shaft. On a standard, m, on the top of the casing D, a hand-lever, n, is pivoted, to which connecting-rods o and o' are pivoted above and below the pivot of the rod n, respectively, the said rods being connected with the two forked levers j. A link, p, connects one lever, j, with an arm, q, of the shaft R. At one end of the shaft R the arm P³ is connected directly with the valve-stem P², but at the opposite end the arm P³ is connected with an intermediate 125 130

lever, P^5 , connected with the valve-stem P^2 , as the movements of the valves P' must be in reverse directions. The steam is conducted through the pipes t to the boxes H . Packing-strips D^4 are held in slots in the top and bottom of the boxes H , transversely of the abutments J , by glands D^5 .

The operation is as follows: As shown in Fig. 3, the wheel A is revolved in the direction of the arrow a' , steam enters through the bottom port Q , acts on the fixed piston E , the abutments J being pressed firmly against the bottom of the groove B . When the above-mentioned piston E arrives at the bottom exhaust-tube G , the steam is exhausted. If desired, the steam may be worked under expansion and cut-off after one-third of the distance between the abutments and the exhaust-tube has been traveled. By the time that the above-mentioned piston E arrives at the exhaust-tube the other piston E has passed the left-hand abutment, which is withdrawn until the piston has passed, and it is then forced forward, the steam acting between the left-hand abutment and the adjacent piston E , which is now above the abutment, and so on, steam being admitted at both ends, and at the right-hand end it is admitted through the bottom port Q , and at the left-hand end through the top port Q . To reverse the engine, the lever n is thrown, whereby the shaft R will be rocked in such a manner as to force the valve P' in the right-hand box H downward and to raise the valve P' in the left-hand box, whereby the steam in the right-hand box will be admitted into the steam-chamber at the top and the steam in the left-hand box at the bottom, and the movement will be reversed. At the same time the sleeves a are moved toward the center of the machine, whereby the inner cams, d , on the sleeves a will be moved inward to such an extent that they cannot act on the inner rollers W^2 of the levers W , and the outer cams, b , will be moved toward the center of the machine such a distance that they act on the outer rollers W' . When the machine is again reversed, the sleeves a are shifted outward, the cam b is moved from the center rollers W^2 , and the cam d is moved outward sufficiently to engage with the inner rollers W^2 . The slide-valves are shifted by the cams $T T'$. The cam T has a play of one-sixth of a revolution on the shaft, so as to permit the shaft to make one sixth of a revolution in the reverse direction before acting on the said cam and before changing the valves. In case a machine has been stopped when acting under expansion in such a manner that the slide-valve N closes the port O , it would be impossible to start the engine. In such a case the free end of the lever S^2 is pressed downward, whereby the valve S' is raised, as shown in Fig. 12, so as to permit the steam to pass from the steam-chest through the aperture S^4 into the channel S^5 , into the port O , the chamber P , and from there to one of the channels Q , according to the position of the valve P' . As soon as steam is admitted into

one of the steam-chambers it starts the machine, and then the machine operates in the usual manner. Steam passes through the steam-chest through the pipes L^3 and the hollow pistons $L^2 L'$ into the cavities L , thereby forcing the abutments J against the bottom of the groove B . Immediately before the piston arrives at the abutment the cam b or d , 75 acting on the lever W , pushes the abutment back sufficiently to let the piston pass, and immediately after the piston has passed the abutment is forced against the bottom of the groove B again, and so on. The motion is 80 transmitted from the shaft to the other parts of the machinery by means of belts passed over pulleys $r r$, or by other devices.

The engine can be reversed very easily. There is no leakage of steam, and all joints are 85 packed securely. The abutments J are withdrawn and forced forward very rapidly, and the pistons fit steam-tight in the groove of the wheel.

Having thus described my invention, what I 90 claim as new, and desire to secure by Letters Patent, is—

1. The combination, with the steam-valves N , of the levers U and the cams $T T'$, mounted on the shaft C , the cam T' being mounted in 95 such a manner as to have play of one-sixth of a revolution on the shaft, substantially as herein shown and described.

2. In a rotary engine, the combination, with a grooved wheel, of a casing surrounding it, 100 which casing is provided with abutment-boxes at diametrically-opposite points, sliding abutments in the boxes, sleeves on the main shaft, cams formed at each end of each sleeve, cam-levers adapted to be acted upon by either cam 105 of each sleeve, and of rods connected with the cam-levers and with the abutments, substantially as herein shown and described.

3. In a rotary engine, the combination, with a grooved wheel, of a casing surrounding it 110 and provided with abutment-boxes at diametrically-opposite points, sliding abutments in the boxes, the sleeves a on the shaft C of the wheel, the cams $b d$ on the sleeves, the cam-levers W , provided with the rollers $W' W^2$, 115 and rods connected with the said levers, and with abutments, and of levers for shifting both sleeves at the same time, substantially as herein shown and described.

4. In a rotary engine, the combination, with 120 a wheel, of a casing surrounding it, abutments in the casing, hollow pistons projecting into cylinder-apertures in the abutments, and pipes for conducting steam through the hollow pistons into the cylinder-apertures, substantially 125 as herein shown and described.

5. In a rotary engine, the combination, with a wheel, of a casing surrounding it, abutments in the casing, hollow pistons projecting into cylinder-apertures in the abutments, pipes for 130 conducting steam through the hollow pistons into the cylinder-apertures, thus pressing the abutments against the rim of the wheel, and of cams on the shaft of the wheel, and rods con-

nceted with the abutments and acted upon by the said cams for the purpose of pressing the abutments from the shaft of the wheel, substantially as herein shown and described.

5 6. In a rotary engine, the combination, with a wheel, of a casing surrounding it, abutment-boxes provided in the casing, sliding abutments in the boxes, steam-channels formed on the bottom and top of the abutment-boxes, 10 and valves for admitting the steam from the steam-chest into the upper or lower channel, substantially as herein shown and described.

7. In a rotary engine, the combination, with a wheel and a casing surrounding it, of abutment-boxes formed on the casing, sliding abutments in the boxes, the said boxes being provided with steam-channels at the top and bottom of the abutments, a valve for admitting the steam from the chest into either channel, 15 a rock-shaft connected with the said valve, a lever for throwing the rock-shaft, shifting-cams on the shaft of the wheel, rods acted upon by the cams and connected with the abutments, and levers for acting on the shifting-cams and 20 connected with the lever for throwing the rock-shaft, substantially as herein shown and described.

8. In a rotary engine, the combination, with a wheel and a casing surrounding it, of abutment-boxes formed in the casing, sliding abutments in the boxes, the sliding valve N, working in the steam-chest M, the valve P', working 25 in the chamber P, connected with the

steam-channels Q Q', and the valve S', working in a channel, S, establishing communication 35 between the steam-chest M and the chamber P, for the purpose of starting the machine, substantially as herein shown and described.

9. In a rotary engine, the combination, with the grooved wheel, of a cylindrical casing surrounding it, and the pistons E, formed in the groove by two transverse partitions, covered by 40 a top plate on which a packing-plate is held, substantially as herein shown and described.

10. In a rotary engine, the combination, with 45 the wheel A, having a groove in its rim, of the two piston-walls E', the cross-piece E², the packing-plate F, the pins F', projecting from the packing-plate F through the cross-piece E², and the springs F³, for pressing the packing-plate against the bottom of the groove, substantially 50 as herein shown and described.

11. In a rotary engine, the combination, with the wheel A, having a groove in its rim, of the piston-walls E' E', having apertures e', the 55 cross-piece E², having a groove, e, and an opening, e', the valve f, held in the groove e, the packing-plate F on the cross-piece E², and the springs for pressing the packing-plate against the cross-piece E², substantially as herein 60 shown and described.
